UNITED STATES PATENT OFFICE

ELBERT J. HALL, OF DETROIT, MICHIGAN, ASSIGNOR TO AMERICAN CAR AND FOUNDRY
MOTORS COMPANY, OF NEW YORK, N. Y., A CORPORATION OF DELAWARE

CAR CONSTRUCTION

Application filed June 13, 1928. Serial No. 285,078.

This invention relates to improvements in car construction and comprises certain features of novelty in the detail construction and arrangement thereof, all as hereinafter more fully described and specifically pointed out in the claims. An object of the invention is to provide in car construction a rigid body portion for passenger carrying purposes wherein the side and end walls of the car form the supporting means adapted to be carried directly upon the wheels and axles without the intervention of the usual bogie or swiveling car truck and in which the body portion of the car comprises deep plate girder construction interrupted only to provide doors affording ingress and egress.

Another object of the invention is to provide a car of the type hereinbefore referred to which is self-contained and in which a motor, either electrical or otherwise, may be carried within the body of the car as is common in so-called rail cars which are now being introduced in large numbers and in which the motor is generally a gasoline engine.

25 In the drawings:

Figure 1 is a plan view of approximately one half of a car of the type hereinafter more fully described, the vertical walls, posts, etc., being shown in section;

30 Figs. 2 and 3 are sectional views of the opposite end of the car in which the passengers enter, showing in detail the entrance or step well hereinafter more fully described;

35 Fig. 4 is a sectional view illustrating the connection of the wheel hoods, hereinafter referred to, to the plate girder side walls of the car;

40 Figs. 5 and 6 are respectively the upper and lower portions of a single vertical sectional view taken through the side wall of the car showing the plate girder construction from the lower tension member thereof up to the window opening and the reinforcements above said opening;

45 Fig. 7 is a transverse sectional view taken on the line 7—7 of Fig. 5;

Fig. 8 is an enlarged vertical sectional view in duplication of the elements shown in the lower portion of Fig. 5 above the broken line, 50 but upon a greatly enlarged scale;

Fig. 9 is a duplication of the portion of Fig. 5 below the broken line upon the same scale as Fig. 8;

55 Figs. 10, 11 and 12 are enlarged sectional views taken respectively on section lines 10—10, 11—11 and 12—12 of Figs. 8 and 9;

Fig. 13 is a transverse vertical sectional view through the underframe portion of the car taken somewhere in the vicinity of the section line 13—13 shown on Fig. 1;

60 Fig. 14 is a similar view of a detail, the section being taken approximately on the line 14—14 of Fig. 1;

Fig. 15 is a longitudinal sectional view, the section being taken on the line 15—15 of Fig. 14;

65 Fig. 16 is a sectional view similar to Fig. 13 showing details hereinafter specifically described;

70 Fig. 17 is a vertical longitudinal sectional view taken substantially on line 17—17 of Fig. 1;

75 Fig. 18 illustrates reinforcement for the plate girder hereinafter referred to at the end where the same is cut out to accommodate the radiator; and

Fig. 19 is a vertical longitudinal sectional view taken substantially on the line 19—19 of Fig. 1.

80 It has been conventional in street car construction to provide a pair of trucks, one at each end, each provided with a truck bolster adapted to engage with and support body bolsters, which body bolsters in turn are the sole supporting means for the body of the car. In such construction the motor is usually carried upon the truck and for certain purposes requiring an unnecessary weight of material.

In the present instance, wheels and axles 1—2 are the primary supports and suitable means, 85 preferably in the form of bearings 2' carrying hangers 3' provide for supporting on the axles longitudinally extending springs 3, the rear ends of which are connected by means of

spring shackles 4—5 with transoms 6, which transoms in the present instance are of tubular form and are either welded at 7 or are otherwise connected with flanged end portions 8, which latter are in turn connected by

90 suitable rivet connection 9 with side plate 10.

95

girders 10. There are interposed between the members 8 and said side plate girders shims 11, and outside of the plate girders supplemental reinforcing plates 11A are provided to stiffen the plate of the plate girder 10 at the point of connection therewith. This reinforcing plate is not so essential if a relatively thick and heavy plate 10 is used in the plate girder, but in a construction of the type herein referred to it is desirable to keep the weight of the structure as at low a point as possible and for that purpose the plate girder employs sheets or plates of as light a gauge as is consistent with safety and the plate girder is reinforced by means of the plates 11 over a sufficient area which may be larger than the headed portion 8 of the member 6 to provide a proper factor of safety in the completed structure.

It is understood that the members 6 are connected at each end to the opposite plate girders forming the lower wall portion of the car and serve as the supporting means upon the springs before referred to for the superstructure or body of the vehicle. Mounted upon the transoms 6 and connected therewith and to the spring shackle portion 5 are floor supports 14 which are connected by the bolts 15 with the upper rigid portion of the spring shackles. As shown in Fig. 19, each of the springs 3 is pivotally connected at its forward end to a bracket 5' which is clamped about a transom 6 to a floor support 14 in any approved manner, as by means of bolts 15. The members 14 are duplicated at each side of the longitudinal central line of the body, and intermediate the members 14 similar members 16 are connected by means of the straps 17 with said transoms 6. The members 14 and 16 directly support longitudinally extending channels, preferably rolled sections 18, which, except where they are interrupted by cross members hereinafter referred to, are continuous from end to end of the car body, and in said channels nailing strips 19 of wood are provided to serve as floor nailing strips to which the flooring 20 is secured.

Connected with the outer ends of the transoms 6, the plate girders 10 comprise bottom chords, or tension members 22, vertical posts of T-shape in cross section 23 having their double flanges 24 extending longitudinally of the car, and with their single intermediate flanges 25 extending inwardly and transversely of the car, as best shown in Figs. 10, 11 and 12. The plate of the plate girder sides extends from the bottom chord 22 upwardly to the window opening, below which is secured the belt rail 27 which is continuous throughout the entire length and around the ends of the car, except as it is interrupted for door openings. The belt rail 27, therefore, forms a top chord, or compression member of the plate girder 10. Supplementing the belt rail 27 as a top chord, or compression mem-

ber are sill angles 28, which except as they are interrupted by the inner flanges 25 of the T-shaped side posts, are continuous from end to end of the car. Bolted upon the flanges 28 by means of the bolts 29 are window sill strips 30 provided at each window opening along the sides of the car and upon these strips 30 at each window opening are cover strips 31 which are flanged upwardly at 32 to provide a weather strip with the conventional arm rest 33 resting upon the inturned flange of the members 31.

The side posts before referred to are continuous from the bottom chord 22 on one side to the corresponding bottom chord on the opposite side of the body and form the carlines of the body. Secured to the carlines are the conventional purlines 35, and secured to each side of the vertical downwardly extending flange portions 23-A are provided nailing strips 36 which are connected by the bolts 37 with said web portions 23-A of the combined posts and carlines. To these nailing strips is secured the roof 38-A in any suitable manner and where the roof terminates at the sides there is provided a series of longitudinally extending wood reinforcing members 38 which are slotted to accommodate the inturned flanges 25 of the body posts, the said member 38 or its continuations being substantially continuous from end to end of the body. Connected with said members 38 and serving as drips for the roof are members 39 upon which are secured battens 40, as best shown in Fig. 5. Below the members 38 to 40, inclusive, there are provided side plates 41 flanged at 42 for direct connection with the members 38 by means of the bolts 43 and secured by means of the rivets 44 directly to the longitudinal extending flanges 25 of the body posts, thereby with said members 38 connecting and reinforcing the body superstructure in its upper portion, being somewhat assisted by the watershed 45 flanged outwardly over the wood strips 46 as shown in Fig. 5. Thus there is provided a very light superstructure which when properly supported affords the necessary protection against the weather.

The plate girder is of substantial depth, and, though it is necessarily interrupted at the doors, it is reinforced within the zone of the door openings by means of transverse beams or girders 50 which are connected with the flanges 25 of the posts 23 and extend entirely across the car from side to side, thus forming auxiliary stiffening members at each side of the door opening. To the transverse members 50 are connected the plates 51 of the step well by means of the angles 52 riveted respectively to said members 50 and 51, and it is to be noted that the plate 51 is bent to a horizontal position (as best shown in Fig. 2) at 51-A to form a step. Within the zone of the step well and door opening

before referred to, the angle 53 is provided, which is connected directly with continuations of the bottom chord 22 of the plate girder at each side of the door opening, thereby, with the transverse members 50 and the parts 51 and 51—A, substantially reinforcing the plate girder where the door openings are provided. While they are not shown in the drawing, it is understood that similar transverse members 50 may be provided as may be required extending transversely of the underframe from side plate girder to side plate girder entirely across the car.

Additional stiffness is imparted to the plate girder construction by means of the wheel hoods 60 which are connected by means of the angles 61 directly to the plate girders 10, and to further stiffen said parts the channels 18 at each side of the car are connected by means of the rivets 62 with the vertical sheets of said wheel hoods 60 thereby tying the wheel hoods to the flooring and connecting the same to the side plate girders to reinforce the latter.

Though it is entirely optional where the radiator may be placed, there is shown in Fig. 18 a radiator 65 with fans 66 mounted upon shafts carried in the angles 67, which angles serve as means for transmitting stresses in the plate girder construction by reason of their connection with the vertical angles 68, and this construction is reinforced by the bottom angle 69 upon which rests the end portions of the channels 18 before referred to, said channels being secured thereto by suitable rivet connection.

Contributing to the stiffness of the body structure at the rear end is a baggage compartment 70 secured by suitable rivet connection with the angles 71 and with the channels 18.

Thus there is provided a rigid body shell comprising a plate girder load carrying portion provided with top and bottom chords and intermediate said top and bottom chords there is provided angle floor supporting members 72 connected by the rivets 73 with the plate girder and contributing to the stiffness thereof at the same time serving as supports for the floor nailing strips 74 connected with the angles by the vertical bolts 75.

Supplementing the channels 18 as floor supports there are provided a plurality of pressed channel members 77 having outwardly disposed horizontal flanges 78, which transverse channel members are connected by means of gussets 79 suitably riveted thereto and to the longitudinal channels 18 before referred to.

Within the trough portions of the channels 77 are wood nailing strips 18—A to which the flooring may be secured. Connected at suitable intervals throughout the length

of the body structure are gussets 80 connected by rivets 81 and 82 with said channels 77 and with the inturned flanges 25 of the body posts, thereby connecting the transverse members 77 with said posts and the plate 70 girder sides and contributing materially to the stiffness of the latter.

It is obvious that the hereinbefore described connection of the wheel hoods and the plates of the plate-girder side walls, together with the connection of the hoods with the channels 18 and the connection of the latter with the tubular transoms 6 connected to the said plates provides a rugged construction admirably adapted to transmit buffing and pulling stresses as for example upon application of brakes and in driving, in the event of power being applied to the axle 2.

The specific construction shown in the drawings is the preferred form of the invention, though it is to be understood that various modifications in the details illustrated and described may be made, as it is obvious that such modifications will suggest themselves to one skilled in the art and it is my intention to cover the construction as broadly as possible within the scope of the following claims.

What is claimed is:

1. In a car, a rigid body shell comprising 95 a plate girder load carrying portion provided with compression and tension members, vertical T-shaped posts riveted to and stiffening said girder extending thence upwardly and across the car body to form carlines, relatively continuous wood fillers interposed between said posts, body supporting means extending transversely thereof and being secured to said plate girders, axles, and longitudinally extending springs mounted on the 100 axles and connected to said supporting means.

2. In a car, a plate girder body construction, transverse body supports, longitudinally extending leaf springs flexibly connected 110 with said supports and axles directly supporting said leaf springs.

3. In a car, a plate girder body construction, transverse body supports riveted directly to the inner faces of the plate girder, 115 longitudinally extending leaf springs flexibly connected with said supports and axles directly supporting said leaf springs.

4. In a car, plate girder side walls, a plurality of transverse floor supports connected thereto, longitudinally disposed channels secured upon said supports with their flanges upwardly disposed, wood nailing strips in said channels, axles, springs supported directly above said axles, and spring shackles connecting the springs with transoms connected 120 with said plate girder walls.

5. In a car, axles, springs extending longitudinally of the car mounted on said axles, 130 transversely extending body supports with

- which said springs are flexibly connected and a plate girder body inflexibly connected to the ends of said body supports.
6. In a car, wheels, axles, leaf springs mounted on the axles, a body including plate girders, transoms connecting the plate girders, and spring shackles connecting the springs and transoms. 70
7. In a car, plate girder sides including continuous posts and carlines, a plurality of transoms connected directly to the inner face of said plate girder sides, wheel housings connected with said plate girders and floor supporting channels connecting said transoms some of which are connected directly to said wheel housings. 75
8. In a car, plate girder side walls, transoms connecting said walls, spring shackles supported on said transoms, leaf springs connecting said shackles and an axle upon which said springs are directly mounted. 80
9. In a car, plate girder side walls, transoms connecting said walls, wheel housings connected with said plate girders and floor supports connecting the housings with some of the transoms. 85
10. In a car, plate girder side walls, including continuous posts forming carlines of T-shape in cross section, a side plate having an inturned upper flange, and a substantially continuous wood filler to which said upper flange is connected. 90
11. In a car, plate girder side walls, transoms terminating in flanged enlargements, metallic reinforcing plates interposed between said enlargements and said plate girder and rivets connecting all of said members. 100
12. In a car, plate girder side walls of relatively thin sheets, transoms connecting said walls said transoms comprising tubular members with cast metal flanged end extensions of greater area than the cross section of the tubular members and metallic reinforcing plates interposed between and connected directly with the end extensions and the plate girders. 105
13. In a car, girder supporting walls including bottom chords and plates connected therewith and body supporting transoms connected directly to said bottom chords and with said plates and reinforcing plates interposed between the plates and transoms. 110
14. In a car construction plate girder side walls including wheel hoods. 115
15. In a car construction, plate girder side walls, floor supporting members and wheel hoods comprising portions of the plate girders connected with said floor supports. 120
16. In a car construction, plate girder side walls, transoms connecting said walls, springs and other longitudinal members connecting said transoms, and wheel housings connecting said longitudinal members with the plate girder side walls. 125
17. In a car construction, a rigid plate
